(57) **CLAIM**

The ornamental design for a wireless communication adapter, as shown and described.

DESCRIPTION

FIG. 1 is a perspective view of a wireless communication adapter showing our design in an extended state with the audio jacks in a first deployed position, as viewed from the top and front.

FIG. 2 is a front view thereof.

FIG. 3 is a back view thereof.

FIG. 4 is a left side view thereof.

FIG. 5 is a right side view thereof.

FIG. 6 is a top plan view thereof.

FIG. 7 is a bottom plan view thereof.

FIG. 8 is a perspective view of a wireless communication adapter showing our design in an extended state and with the audio jacks in a second deployed position, as viewed from the top and front.

FIG. 9 is a front view thereof.

FIG. 10 is a back view thereof.

FIG. 11 is a left side view thereof.

FIG. 12 is a right side view thereof.

FIG. 13 is a top plan view thereof.

FIG. 14 is a bottom plan view thereof.

FIG. 15 is a perspective view of a wireless communication adapter showing our design in a collapsed state and with the audio jacks in the first deployed position, as viewed from the top and front.

FIG. 16 is a front view thereof.

FIG. 17 is a back view thereof.

FIG. 18 is a left side view thereof.

FIG. 19 is a right side view thereof.

FIG. 20 is a top plan view thereof.

FIG. 21 is a bottom plan view thereof.

FIG. 22 is a perspective view of a wireless communication adapter showing our design in a collapsed state and with the audio jacks in the second deployed position, as viewed from the top and front.

FIG. 23 is a front view thereof.

(Continued)

FIG. 24 is a back view thereof.

FIG. 25 is a left side view thereof.
